UNITED STATES PATENT OFFICE.

CHARLES HUTCHINSON, OF GREEN ISLAND, NEW YORK.

CASH-RECEPTACLE.

SPECIFICATION forming part of Letters Patent No. 678,620, dated July 16, 1901.

Application filed February 21, 1900. Serial No. 8,005. (No model.)

To all whom it may concern:

Be it known that I, CHARLES HUTCHINSON, a citizen of the United States, residing at Green Island, in the county of Albany and State of New York, have invented certain new and useful Improvements in Cash-Receptacles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 My invention is a cash-receptacle, and differs from what are ordinarily known as "cash-registers" by the fact that it receives the cash, but does not register the amount paid for every single purchase at the time said purchase is made by displaying simultaneous with the action of the plunger a numeral indicating such amount.

20 The objects of my invention are to render the possibilities of stealing the deposited cash as small as possible, to have said receptacle lock itself in case of its being tampered with and to unlock itself automatically, to enable the largest reasonable amount of money to be deposited by means of a tablet system, to furnish a change-drawer separate from the controlling devices that regulate the reception of cash, to render mistakes impossible by furnishing only one key for ringing up the cash deposits, and finally to simplify the coin-admitting means, so that they are cheap to manufacture and easy to repair. How I accomplish these different objects can best be explained in connection with the various means as they will be described in the ensuing description.

25 In describing my improved cash-receptacle I shall call attention to the accompanying drawings, wherein like letters of reference indicate corresponding parts in the different views.

30 Figure 1 shows a section of my receptacle, showing the general arrangement of the interior, the side panel or frame turning toward the spectator being to that effect removed. Fig. 2 is a front view of the receptacle as seen in Fig. 1, given more especially to show the arrangement of the tablets. Fig. 3 is a

top sectional view of the receptacle through the line X X in Fig. 1. Fig. 4 is a side view of the mechanism for controlling the deposit of the coin in the deposit-drawer, shown in about its natural size. Fig. 5 is a front view of said mechanism looking at Fig. 4 in the direction of the arrow Y. Fig. 6 is a top view, partly in section, of the drum and the parts that control and operate it as they are seen in Fig. 5, and Fig. 7 a sectional view on a line Y Y in Fig. 5. Fig. 7 shows a sectional detail view of the upper part of the receptacle, illustrating the slot A⁵ clearly; and Fig. 8, a section on a line X X in Fig. 5.

35 In Fig. 1, A indicates the frame of the receptacle, divided into two compartments A' and A². In the upper compartment the mechanism (shown in enlarged detail in Figs. 4, 5, 70 and 6) is located that controls the admission of the coin first into the space A³ and from thence into the cash-deposit drawer A⁴. Describing this operation more minutely the coin is dropped through the slot A⁵, is caught 75 by the drum B, and deposited in the space A³, and when the plunger-arm C' is manipulated said coin will by a coöperation between the said plunger and a trap-door D be deposited in the underneath-located deposit-drawer A⁴.

40 Referring now to the detailed construction of the plunger mechanism, to which end the enlarged views in Figs. 4, 5, and 6 are furnished, such mechanism will be seen to be 85 constructed as follows: A drum B, having its two journals B' and B² furnished with pulleys B³ and B⁴, so that the journals, the pulleys, and the drum are all one solid part, is pivoted in bearings E² and E³, said bearings 90 formed in arms projecting from the standards E⁴ and E⁵, the journal B² located in the bearing E² of the standard E⁵, and the journal B' located in the bearing E³ of the standard E⁴. Wound around the pulleys B³ and B⁴ and secured to the drum sides at, respectively, points B⁵ and B⁶ are two cords B⁷ and B⁸, each of said cords passing over pulleys B⁹ and B¹⁰, pivoted loosely to the standards F' and F². The other ends of these cords B⁷ and B⁸ are 100 secured to a bar F³, said bar inserted firmly at a right angle to the axis of the plunger C in the plunger C. Coiled around each of the bearings E² and E³ is a spring, G' lying around

E^3 and G^2 lying around E^2 . As these springs are both alike in their action and attachment, it will only be necessary to describe one of them. The spring G' , for instance, has one end secured in the standard E^4 , the other end being secured in the pulley B^3 , and similarly the spring G^2 is affixed between the standard E^5 and the pulley B^4 . It can now be understood that when the drum is revolved by any action on the cords by pulling these in the direction of the arrows Z' and Z^2 and then such pull is stopped the springs G' and G^2 , having during the pull exercised on the cords been contracted, will exercise an expansion movement which will revolve the drum in a direction reverse to the one indicated by arrows Z' and Z^2 —in fact, in the direction of an arrow Z^3 , as observed in Fig. 4.

Referring to the construction of the drum B , it will be seen when looking at Fig. 4 that it has an opening in its circumference stretching across it, as indicated by the letter H , the rest of the circumference being a solid shell. This opening gives admission to a chamber in the drum, which chamber is formed by the flat sides of the drum, the partition-wall H' inside of the cylinder, and the external curved part of the circumferential shell, (marked H^2 .) Into this chamber the coin is dropped, being prior thereto in the slot A^5 and resting on the solid part of the circumference H^2 until the drum-opening H by the action on the plunger-handle C' is swung around to receive it. A shield I , having an opening or slot I' cut therein corresponding in size lengthwise to the opening in the drum, is placed in front of the drum, being attached to the plate J , to which all the other elements similarly are secured. The part I^2 of this shield leads the coin on its downward passage and supports it in front of a transparent partition-wall I^3 , said partition-wall supported between two brackets I^4 . The coin resting there as having been deposited for a certain purchase made can thus be viewed by the purchaser, the whole upper part of the frame A facing these coin-depositing means being to that effect made of glass or other transparent material. The means which support the coin while resting against the part I^2 is a sliding trap-door D , operated from the plunger as follows: Attached to the plate J is standard J' , to which standard is pivoted a lever K ; to whose arm K' there is attached a weight K^2 , said weight K^2 , by means of an arm K^4 , resting on a pin K^3 . This pin K^3 , which will be more distinctly alluded to in connection with the plunger, forms a part of such plunger. The other arm K^5 of the lever K has a link K^6 pivoted to it, which link finally is pivoted to the sliding trap-door D . If consequently the weight K^2 is unsupported—that is to say, if the supporting-pin K^3 , forming part of the plunger C , is withdrawn—the lever K , pivoted in the bracket J' , will necessarily move in the direction of the arrow Z^4 , actuated by the dead-weight of

the weight K^2 , and in so doing will draw the link K^6 , and with it the trap-door D , to which it is attached, thus permitting the coin to drop through the passage D' , which will guide it down into the cash-deposit drawer A^4 , which was the desired object.

The construction of the plunger, which has the two functions of oscillating the drum and withdrawing the trap-door for the deposit of the coin in the drawer A^4 , is as follows: Supported, as above stated, by the cross-bar F^3 is the plunger C , guided by a bearing L , attached to the plate J . Secured at the lowest end of the plunger C is a locking-tongue C^2 , attached to the plunger in such a manner that except the cash-receptacle is kept in an absolutely vertical position the said locking-tongue will prevent the downward movement of the plunger C . The means to attain this end are the following: In the first place, free swinging motion must be given to the said tongue C^2 . This is accomplished, as seen in Fig. 4, by inserting the screw-cut end C^3 of the tongue C^2 into a globular-formed nut C^4 , said nut C^4 resting on the upper edge of a hole C^5 , formed in the bolt C^6 , said bolt C^6 secured in the lower hollow part of the plunger C . Thus the tongue will be given a free swinging motion to all sides. To coöperate with this tongue C^2 , a cup M is furnished, having a centrally-located hole M' , perpendicularly situated directly underneath the suspended tongue C^2 , and a circular channel or groove M^2 , adapted to receive the rounded end of the tongue at the moment the receptacle should be swayed into any position except the true perpendicular. This cup M is secured in a bracket M^3 , suitably secured to the plate J .

Reverting to the action of the sliding trap-door D , it can now be more easily understood that as the weight K^2 , the arm K^4 , and the lever K , all forming one integral part with each other, rest on the pin K^3 , forming an integral part of the plunger C , the lever K will on the downward movement of the plunger C pivot around the pin K^3 in the direction of the arrow Z^4 by the gravitation of the weight K^2 and release the coin by the withdrawal of the trap-door D . In case there should be any desire on the part of the person in charge of the receptacle to abstract any of the deposited cash, it can now be understood that no cash can be deposited unless the plunger C is in a perpendicular position above the hole M' in the cup M , and in case said person or anybody else should desire to abstract a recently-deposited sum of money and should to that effect turn the receptacle upside down the weight K^2 will fall down on the plate J , and consequently keep the sliding trap-door locked.

It can thus be gathered from the foregoing that in the upper part of the receptacle the main and novel features invented by me are the swiveled drum B , the sliding trap-door D , actuated by the lever K and the thereunto-attached weight K^2 , and the plunger C , hav-

ing a suspended rod C² attached to its end, which when actuated by the plunger in their mutual coöperation with each other reduce the chances of theft of the deposited cash and make any effort at tampering with such receptacle absolutely useless.

The lower part of the receptacle A³ contains two drawers A⁴ and R, of which the upper, A⁴, is the cash-deposit drawer, into which the coin transmitted through the slot and downward through the passage D' drops, and the lower is the change-drawer. The drawer A⁴ is regulated in regard to the opening thereof by any ordinary register N. To connect this register operatively with the opening of the drawer, I have devised the following means: The pinion N' as ordinarily used for transmitting the rotative power to the indicator-finger of such register meshes with a spur-gear O, which spur-gear, together with a spur-gear O' of similar size, is mounted loose on a pin O², said pin secured to the side frame of the receptacle. Attached to the drawer A⁴ is a gear-rack O³, with which gear-rack the spur-gear O' meshes. Pivoted to an arm of the spur-gear O' is a pawl O⁴, which pawl during the outward movement of the drawer will engage a ratchet-wheel O⁵, said ratchet-wheel firmly secured to the spur-gear O in any suitable mechanical manner, so as to move simultaneous with O. It can now be seen that when the drawer is pulled out the gear-rack O³ will cause the spur-gear O' to revolve in the direction of the arrow W, and as said spur-gear O' has the pawl O⁴ attached to it the pawl O⁴ will engage the ratchet-wheel O⁵, and as the ratchet-wheel and the spur-gear O are made in one part the gear O, meshing with the pinion N', will operate the indicator-finger of the register or indicator N. The return movement of the drawer will of course have no effect on the register, as the spur-gears O and O', as before stated, are mounted loosely on the pin O². This device will consequently have the effect of establishing the number of times the drawer has been opened. To further establish the fact of any attempt to dislodge money, which a knowledge of the interior of the cash-receptacle of course would reveal as perfectly useless, a device consisting of a cup P and a ball P', lying therein, is attached to the bottom of the drawer, the natural consequence of which being that if the receptacle has been shaken or turned upside down the ball will roll out of the cup, proving beyond a doubt the above-stated motion of the receptacle.

In connection with the change-drawer R, furnished below the deposit-drawer A⁴, I have devised the following means for rendering the deposit of an unusually large sum of money possible without much trouble, and, further, for making only a very small amount of cash change necessary; and, finally, for giving an easy record of outstanding dues, whether large or small, obviating the necessity of any book-keeping or memorizing of such outstanding

accounts and for other practical purposes, as will be understood from the following description: A number of tablets U', U², U³, U⁴, U⁵, 70 and U⁶ are arranged in a rack U. Said tablets have inscribed on them any numeral indicating any amount from five cents up to one hundred dollars, or, if desired, one thousand dollars. The following incident may 75 tend to illustrate the usefulness of this tablet system. A certain person purchases fifty-cents' worth of goods and hands one dollar to the salesman. The salesman deposits the dollar in the change-drawer R and takes out a 80 tablet indicating fifty cents and an ordinary silver fifty-cent piece. The tablet he deposits in the receptacle by depositing it in the slot A⁵ and then manipulates the plunger, 85 which notifies the purchaser that his purchase-deposit is made, the transparent part of the frame showing him the fifty-cent tablet, and the silver fifty-cent piece he hands to the purchaser as his change. The salesman has thus saved fifty cents in currency of 90 the realm as change out of his drawer, his change thus remaining the same, the receptacle holding him accountable for the fifty-cent tablet deposited. As an instance of the greater ease by which larger amounts are deposited in my receptacle, the following will 95 serve to illustrate: Supposing a deposit of one hundred dollars has to be made in my receptacle, the cash-receiver simply deposits a tablet having a hundred-dollar numeral inscribed 100 on it, the depositor being able both to hear and see that it is deposited, and the cash-receiver is held accountable by the machine for the deposited one-hundred-dollar tablet, the currency-bills received by him being kept, 105 for instance, in his change-drawer R. Referring to the blank tablets indicated in the drawing by reference-letters V', V², V³, V⁴, V⁵, and V⁶ in the rack V, their useful and labor-saving qualifications are very apparent. 110 Supposing, for instance, that a customer desires to be credited for his purchase for some reason or other, the operator simply inscribes his name and the amount involved on one of the aforesaid blank tablets, deposits the same 115 in the already-described manner, and at the end of the day or the week, or any desirable period he will know just what amount any such customers have been charged with by counting up the different tablets so deposited, 120 which can then be redeemed, have the amount and name wiped off them, and then be restored to the rack for further use. The old and well-known means for signaling the deposits have been used by me, consisting of 125 the bell-dome S, a standard S', having a lever S² pivoted therein, said lever having one arm S³ furnished with a hammer S⁴ and the other arm with a lug S⁵. This latter lug S⁵ will be depressed by means of a pin S⁶, secured 130 firmly in the plunger C when the latter is manipulated, and when the pin has passed the lug it will be released, letting the hammer S⁴ fall on the bell.

As the coöperation of the different elements with each other has unavoidably been referred to in describing the construction of this invention, no résumé of the same would seem to be necessary.

What I then in accordance with the above description claim, and desire to secure protection for by Letters Patent of the United States, is—

- 10 1. The combination in a cash-receptacle of a single plunger consisting of a projecting lever-arm secured to a vertical downward-extending plunging-rod; with a swiveled coin receiving and transmitting drum operated by said plunging-rod substantially as and for the purposes described.
- 20 2. The combination in a cash-receptacle of a single plunger having a suspended locking-tongue attached, a swiveled coin or tablet receiving and transmitting drum operated by said plunger, a trap-door operated by a weight acting in conjunction with the plunger substantially as and for the purposes described.
- 25 3. The combination in a cash-receptacle of a swiveled coin or tablet receiving and transmitting drum with a single plunger, a loosely-suspended locking-tongue attached to said plunger coöperating with means for locking the receptacle, substantially as and for the purposes described.
- 30 4. The combination in a cash-receptacle of a swiveled drum, a single plunger operating said swiveled drum, a sliding trap-door, a lever moving on a fixed pivot having a weight attached, said weight resting on means secured to the plunger and having connection with the trap-door substantially as and for the purposes described.
- 35 5. The combination in a cash-receptacle of a swiveling coin-receiving drum, a sliding trap-door controlling a passage operated by a single manipulating-arm, a projecting lever-

arm secured to a vertical downward-extending plunging-rod constituting said single manipulating-arm; with a cash-receiving drawer 45 having a register attached operated by means attached intermediate the receptacle-frame and the drawer substantially as described.

6. The combination in a cash-receptacle comprising an upper and a lower compartment of a swiveled drum, a single plunger operating said drum, a trap-door operated by a weighted lever secured in the upper compartment, a coin or tablet depositing drawer having an indicator and intermediate means 55 attached indicating the opening of said drawer and a change-drawer substantially as illustrated and described.

7. In a cash-receptacle, a single manipulating-arm, consisting of a projecting lever-arm secured to a vertical downward-extending plunging-rod operating said receptacle, a swiveling drum controlling a passage, and a sliding trap-door, both operated by said plunging-rod; a series of inscribed and blank 65 tablets adapted to coöperate with the said receptacle substantially as and for the purposes described.

8. In a cash-receptacle, locking means operated by a single manipulating-arm controlling a passage, a register controlling a coin and tablet receiving drawer substantially as described; a series of blank and inscribed tablets adapted to be passed through the said passage substantially as and for the purposes 75 described.

In testimony that I claim the foregoing I have hereunto set my hand this 25th day of November, A. D. 1899.

CHARLES HUTCHINSON.
